Attorney, Agent, or Firm—Todd N. Hathaway

CLAIM

The ornamental design for a hinged spreader assembly with overlay shells for shoes and boots, as shown and described.

DESCRIPTION

FIG. 1 is a perspective view of a hinged spreader assembly with overlay shells for shoes and boots showing my new design;

FIG. 2 is a top plan view thereof, wherein the broken line image showing the expander is for illustrative purposes only and forms no part of the claimed design;

FIG. 3 is a right side elevational view of the hinged spreader assembly with overlay shells;

FIG. 4 is a bottom plan view thereof;

FIG. 5 is a left side elevational view thereof;

FIG. 6 is a forward end elevational view thereof; and,

FIG. 7 is a rearward end elevational view thereof.
